UNITED STATES PATENT OFFICE.

LUTHER CUNNINGHAM, OF SAN JOSÉ, AND ROBERT GUY SMITH, OF SARATOGA, CALIFORNIA, ASSIGNEES TO EDWARD LE QUESNE, OF SARATOGA, CALIFORNIA.

FRUIT-GRADING MACHINE.

SPECIFICATION forming part of Letters Patent No. 583,981, dated June 8, 1897.

Application filed November 20, 1896. Serial No. 612,840. (No model.)

To all whom it may concern:

Be it known that we, LUTHER CUNNINGHAM, of San José, and ROBERT GUY SMITH, of Saratoga, in the county of Santa Clara, State of California, citizens of the United States, have invented certain new and useful Improvements in Fruit-Grading Machines, of which the following is a specification.

Our invention relates to an organized machine and apparatus for automatically grading or selecting green or dried fruit, according to its size or dimensions.

Our improvements consist in double or compound screen-frames set one above the other, having a coincident but opposite reciprocating movement; a lateral and a vertical or jarring motion, all imparted by cams; also, in various accessory devices that will hereinafter be particularly explained in connection with the drawings accompanying and forming a part of this specification.

The objects of our invention are to provide within a given length and within one machine double the usual length of screen-surface, so as to repeat the selecting or grading of the fruit, to attain the various motions of screen-frames by simple and inexpensive devices, and to secure a rapid and efficient performance in grading or selecting the fruit.

Referring to the drawings, Figure I is a side elevation of a fruit-grading machine constructed according to our invention. Fig. II is a plan view of the same machine. Fig. III is a transverse section on the line $x-x$ in Fig. I. Fig. IV is another transverse section on the line $y-y$ in Fig. I. Fig. V is a side view of one of the links on which the screen-frames are supported. Fig. VI is an enlarged side view of one of the cam-yokes that actuate the screen-frames.

1 is the main frame of the machine, preferably made of wood, in the form seen in Figs. I and II, having an inclined rail 8 at the top, to which is attached the main operating parts of the machine.

2 and 3 are cradles or screen-frames provided with bottoms formed of perforated plates or screens 25. The holes therein, through which the fruit passes, are of varied diameter, increasing in size from the higher

to the lower end of the screen-frames, as seen in Fig. II. At the highest end is provided a grated screen 26, through which pass leaves, stems, dust, or other waste matter of the kind that may be among the fruit. The screen-frames 2 and 3 are supported on the trunnions 4 and the links or levers 5, as shown in Figs. I, IV, and V. These links 5 are preferably made in sigmoidal form, as shown in Figs. I and V, to permit some flexure in the plane of movement, and are loosely supported on the shafts 6, that extend across the machine and are held in the bearings 7, attached to the top rail 8 of the machine-frame 1. The links 5 fit loosely on the shaft 6, so as to turn 65 and slide freely thereon, being made with an oblong bore, as seen in Fig. V, to permit some vertical movement of these links and of the screen-frames 2 and 3, suspended thereon.

To the bottom of the lower screen-frame 3 we 70 attach cam-yokes 11, (shown enlarged in Fig. VI,) provided with downward-projecting extensions 12 and 13, that embrace at each side the cams 14, one of these extensions 13 being bent, as shown in Fig. IV, to insure engagement of the cams 14 on their upward stroke. These cams 14 are fixed on a shaft 15 and are set obliquely thereto, as seen in Fig. IV, so that when in rotation the yokes 11 are moved longitudinally with respect to the screen-frames 2 and 3, as indicated by dotted lines in Fig. VI, also from side to side at each revolution of the shaft 15 because of the oblique position of the cams 14, causing a corresponding lateral motion of the screen-frame 3 and 80 also of the screen-frame 2, communicated to the latter by means of the links 5, which slide freely on the shafts 6 when at the same time turning thereon.

In the center of the cam-yokes 11 we provide downward-projecting lugs 16, that are engaged at the top by the cams 14 at each revolution of the latter, giving an abrupt blow and short upward movement of the screen-frames 2 and 3, which fall with a shock and thus loosen any fruit that may be lodged in the screens 25, also dislodge any waste matter in or on the grating 26.

At the forward or feeding end of the machine we provide a chain or endless elevator 100

17, passing around the axes 21 22, driven by a pulley 22 and a band 23, connecting to a pulley 20 on the shaft 15.

To drive the machine, power is applied to 5 the end 19 of the shaft 15 by means of a hand-crank or otherwise, all movements being communicated from this shaft.

In operating the machine the fruit is placed in the bin 27 and is carried up by the conveyor or elevator 17 and falls on the grated screen 26, where the meshes are small enough to permit the passage of leaves, stems, or dirt contained in the fruit, but not of the fruit itself, which by reason of the inclination and agitation of the screen-frame 2 passes on slowly over the perforated plates 25, most that is small enough falling through the first plate and the remainder going on to the next, and so on, down to the last screen, which has 20 perforations large enough to pass the largest fruit.

The fruit passing through the top screen-frame 2 falls on the lower screen-frame 3, where a second selection or grading takes place. The opposite screens 25 in the lower screen-frame 3 being one degree or grade less than those above, the selection or grading is repeated. So the operation being double is more rapid, complete, and a greater amount 30 of fruit can be treated in a given time than if but one screen-frame was employed. Beneath the screen-frame 3 are placed bins or receptacles 28, into which the graded fruit falls, also a bin 29 to catch the waste material 35 passing through the grating 26.

Any of the fruit which by reason of abnormal size, or is flattened by crushing, fails to pass through the screens goes on over them and into a receptacle provided for that purpose.

The screens 25 are preferably made of sheet metal having circular perforations, as shown in Fig. II, but may be made of woven wire or in any other manner that will permit the fruit 45 to pass through in proportion to its size.

The screen-frames 2 and 3, having coincident and opposite reciprocating movement longitudinally and being nearly balanced, do not produce vibration common to the reciprocating elements of such machines and can 50 be operated without producing vibration of the main frame or of a building in which the machine is operated.

Having thus described our invention and 55 its objects, we claim—

1. In a fruit-grading machine, the combination of the parallel inclined screen-frames with graduated meshes or openings, the vibrating links connecting the said frames, pivoted loosely at the center on cross-shafts, and 60 means for imparting coincident longitudinal, vertical and lateral motions to the said frames, substantially as specified.

2. In a fruit-grading machine, the combination of the parallel inclined screen-frames, 65 the vibrating links connecting the said frames, pivoted at the centers on oblong bearings permitting of coincident longitudinal, vertical and lateral motion, and means for imparting to the said frames the said motions, substantially as specified.

3. In a fruit-grading machine, the combination of the parallel inclined screen-frames with graduated openings, the vibratory links connecting the said frames, pivoted at the 75 centers on oblong bearings permitting of vertical and lateral motion, cam-yokes on the lower screen-frame, cams 14, and means for rotating said cams, whereby rapid longitudinal and lateral reciprocating motions are imparted to the said screen-frames, substantially as specified.

4. In a fruit-grading machine, the combination of the parallel inclined screen-frames with graduated openings, the vibrating links 85 connecting the said frames, pivoted at the centers on oblong bearings permitting of vertical and lateral motion, cam-yokes 11, cams 14, set eccentric on cross-shaft 15 and also inclined to the axis of said cross-shaft, with 90 means for rotating said cams, whereby rapid longitudinal and lateral reciprocating motions are imparted to the said screen-frames, substantially as specified.

5. In a fruit-grading machine, the combination of the parallel inclined screen-frames with graduated openings, vibrating links 5 pivoted to the said frames and having vertically-oblong central bearings on shaft 6 permitting of vertical and lateral motion, cam-yokes 11, and cams 14 set eccentric on cross-shaft 15, and also inclined to the axis of the 95 said shaft, driving-shaft 21, gear connections with cam-shaft 15, and endless-chain elevator 17, substantially as specified. 105

6. In a fruit-grading machine, the combination of the parallel inclined screen-frames with graduated openings, vibrating links 5 pivoted to the said frames and having vertically-oblong central bearings on shaft 6 permitting of vertical and lateral motion, cam-yokes 11, lugs 16, cams 14 set eccentric on cross-shaft 15, and also inclined to the axis of the 110 said shaft, driving-shaft 21, gear connections with cam-shaft 15, endless-chain elevator 17, a series of graduated receptacles 115 28, and bin 29, all substantially as specified.

In testimony whereof we have hereunto affixed our signatures in the presence of two witnesses.

L. CUNNINGHAM.
